UNITED STATES PATENT OFFICE.

NILS BERGLUND, OF FITCHBURG, MASSACHUSETTS, ASSIGNOR TO MARY ELIZABETH JOHNSON, OF SAME PLACE, EXECUTRIX OF IVER JOHNSON, DECEASED.

DESIGN FOR A BICYCLE FORK-CROWN.

SPECIFICATION forming part of Design No. 30,450, dated March 28, 1899.

Application filed February 28, 1899. Serial No. 707,223. Term of patent 7 years.

To all whom it may concern:

Be it known that I, NILS BERGLUND, a subject of the King of Sweden and Norway, residing at Fitchburg, in the county of Worcester and Commonwealth of Massachusetts, have invented and produced a new and original Design for Bicycle Fork-Crowns, of which the following is a specification.

The design relates to the shape or configuration of a bicycle fork-crown, as represented in the accompanying drawings, in which—

Figure 1 represents a front elevation of a bicycle fork-crown embodying my design. Fig. 2 is a top view of the same. Fig. 3 is a central sectional view on line 3 3, Fig. 2; and Fig. 4 is a bottom view.

Similar letters refer to similar parts in the several views.

The essential feature of my invention consists of two vertical parallel sides, which are oval in their cross-section, connected near their ends by two curved or arched members of approximately the same curvature with the upper ends of said straight sides projecting above the upper curved member, so as to form horizontal shoulders, together forming a double-arch crown with the ends of each of the arched members merging into the vertical sides.

30 A A represent the vertical sides, which are oval in cross-section, as represented at A' A', Fig. 2.

B denotes the upper curved member of the double-arch crown, provided with a circular hole B' and having a circular raised shoulder B² and a circular hub B³ concentric with the hole B'.

C denotes the lower curved member, having a circular hole C' beneath the hole B' in the upper curved member B.

40 The curvature of the upper and lower members B and C are approximately the same, so that the ends of the arched members, if produced, would meet at some distance outside the vertical sides A A, and the ends of the 45 curved portions are united to the vertical sides A A, with the curved planes of the members B and C cutting the vertical plane of the sides A A. The upper curved member B is oval in cross-section with its edges thinner than 50 its center, while the lower curved member C is substantially of the same thickness throughout its entire width.

55 The opposite edges of both the upper and lower curved members B and C present curved outlines, said members being slightly wider through their central section than at their ends, as shown by the curved lines D D' and E E' in Figs. 2 and 4. The upper ends of the vertical sides A A form horizontal projecting 60 shoulders A' A', presenting horizontal planes cutting the curved upper surface of the curved member B.

I claim as my invention—

65 The design for a bicycle fork-crown herein shown and described.

Dated this 20th day of February, 1899.

NILS BERGLUND.
